UNITED STATES PATENT OFFICE.

JAMES A. WESTMORELAND, OF VIVIAN, LOUISIANA.

SUCKER-ROD HOOK.

Application filed November 10, 1924. Serial No. 748,897.

To all whom it may concern:

Be it known that I, JAMES A. WESTMORELAND, a citizen of the United States, residing at Vivian, in the parish of Caddo and State of Louisiana, have invented certain new and useful Improvements in Sucker-Rod Hooks; and I do declare the following to be a full, clear, and exact description of the invention, such as will enable others skilled in the art 10 to which it appertains to make and use the same.

My invention relates to improvements in hooks such as those used on numerous kinds of hoisting devices and the like, and the 15 present disclosure is directed to a hook which is designed primarily for hoisting sucker rods, although the construction shown is by no means limited to this use.

It is the object of the invention to provide a simple and inexpensive, yet a very desirable structure embodying a guard for the hook which normally prevents it from disengaging from the member with which it is engaged, and to provide novel, manually 25 controlled releasing means for the guard, said means also acting, in the present disclosure, to hold the guard in operative position.

With the foregoing in view, the invention 30 resides in the novel subject matter herein-after described and claimed, the description being supplemented by the accompanying drawing.

Figure 1 is a side elevation of the improved hook engaged with the usual stirrups of a sucker rod elevator.

Figure 2 is a vertical sectional view, partly in elevation showing the guard moved to released position.

Figure 3 is an edge view partly broken away and in section.

In the drawing above briefly described, the numeral 1 designates the shank of the hook, which shank is provided at its lower end 45 with a bill 2 in opposed relation with the front edge of the shank. The upper end of this shank has been shown suitably swiveled at 3 to a plate 4 which is pivotally mounted in a hoisting yoke 5, connected with a part 50 6 of a hoisting mechanism. It will be understood however that the hook could well be carried by a part or parts other than those shown.

At 7, a U-shaped guard has been shown, 55 said guard normally extending across the throat of the hook and having its two arms

8 pivoted against opposite sides of the shank 1, as indicated at 9, the pivotal connections being disposed between the ends of the arms 8, but adjacent the free ends of said arms, 60 which ends are preferably of substantially circular form as indicated at 10.

A releasing device 11 is provided for the guard 7, said releasing device comprising an elongated back 12 spaced outwardly from the rear edge of the shank 1, and a pair of spaced side walls 13 which are preferably integral with said back and project therefrom into engagement with opposite sides of the hook shank. In the present disclosure, the lower ends of the walls 13 are formed with notches 14 loosely receiving the rounded ends 10 of the guard arms 8, so that when the device 11 is forced from the position of Fig. 1 to that of Fig. 2, the guard 75 will be released.

I employ means movably mounting the releasing device 11 upon the shank 1, said device being preferably pivotally mounted at its upper end. To accomplish this mounting, I have illustrated a lug 15 extending rearwardly from the upper end of the shank 1, into a recess 16 in the upper end of the back 12, a pin 17 being passed through said lug and through the upper end of the back 80 12, as shown.

A spring 18 is confined between the shank 1 and the back 12 for the purpose of normally moving the device 11 outwardly to the position of Fig. 1, so as to hold the guard 85 8 in operative position. This spring is preferably formed from a strip of spring metal bent upon itself with its reaches disposed in contact with the shank 1 and back 12 respectively and said shank is by preference 90 provided with a shoulder 19 at the lower end of the releasing device 11, which shoulder engages the free end of one reach of the spring 18 while the lug 15 is disposed at the opposite end of the spring. Thus, this 95 spring is positively held against dislocation and loss.

The parts normally stand as shown in Fig. 1, so that the hook is held against release from the usual stirrups 19 of a sucker rod 100 or tubing elevator, or any other member or members with which said hook may be engaged. When the hook is to be released, the releasing device 11 is forced inwardly toward the shank by hand, so that the guard 105 7 is moved to an inoperative position as shown in Fig. 2.

The device is simple and inexpensive, yet will be reliable and in every way desirable, and as excellent results are obtained from the details disclosed, they are preferably followed. However, within the scope of the invention as claimed, numerous modifications may be made.

I claim:

1. A device of the class described comprising a hook having a shank and a bill in opposed relation with a part of said shank, a U-shaped guard for the bill having its two arms pivoted between their ends to opposite sides of the shank, a releasing device 15 for the guard comprising a back spaced outwardly from the rear edge of the shank, and spaced side walls extending from said back and disposed at said sides of the shank, said walls having pivotal connection with the 20 free ends of the aforesaid arms of the guard for releasing the latter when said back is forced toward the shank, means movably mounting said releasing device on said shank, and a spring confined between said back and said shank for normally forcing the former outwardly.

2. A device of the class described comprising a hook having a shank and a bill in opposed relation with a part of said shank, 30 a U-shaped guard for the bill having its two arms pivoted between their ends to opposite sides of the shank, a releasing device for the guard comprising a back spaced outwardly from the rear edge of the shank, and spaced side walls extending from said back and disposed at said sides of the shank, said walls having notches loosely receiving the free ends of the aforesaid arms to move

the guard to released position when the aforesaid back is forced toward the shank, 40 means movably mounting said releasing device on said shank, and a spring confined between said back and said shank for normally forcing the former outwardly.

3. A device of the class described comprising a hook having a shank and a bill in opposed relation with a part of said shank, a U-shaped guard for the bill having its two arms pivoted between their ends to opposite sides of the shank, a releasing device 50 for the guard comprising a back spaced outwardly from the rear edge of the shank, and spaced side walls extending from said back and disposed at said sides of the shank, said walls having pivotal connections with the 55 free ends of the aforesaid arms of the guard for releasing the latter when said back is forced toward the shank, means pivotally connecting one end of said releasing device to the shank on an axis parallel to the pivotal axis of the aforesaid arms, said shank having a shoulder at the other end of said releasing device, and a strip of spring metal bent upon itself and confined between the 60 aforesaid back and said shank with its two reaches contacting therewith respectively, the free end of one of said reaches abutting the aforesaid shoulder to prevent endwise movement of the strip in one direction, the 65 pivotal connection between said releasing member and the shank being disposed to prevent movement of the strip in the other direction.

In testimony whereof I have hereunto affixed my signature.

JAMES A. WESTMORELAND.
